FIREARM

Kenji Murakami, 458 Hiyoshi-cho,
Kohoku-ku, Yokohama, Japan

Filed Nov. 2, 1970, Ser. No. 25,793

Claims priority, application Japan May 16, 1970

Term of patent 14 years

Int. Cl. D22—01

U.S. Cl. D22—6

FIG. 1

FIG. 2

FIG. 3

FIG. 1 is a side elevational view of a firearm showing my new design, the opposite side being identical;

FIG. 2 is an enlarged side elevational view thereof the firearm being fragmentarily shown for convenience of illustration;

FIG. 3 is a cross-sectional view taken on line 3—3 of FIG. 2;

The cross-hatching on the forearm stock surface ornamentation is partially shown for convenience of illustration, it being understood that the cross-hatching is continuous over said area.

I claim:

The ornamental design for a firearm, as shown and described.
